7 Claims. (Cl. 149—92)

The present invention relates to a high explosive body and to a method of making the same.

The explosive mixtures which are used for producing high explosive bodies consist usually of two components, namely one explosive composition which has a relatively high melting point and frequently does not melt without decomposition, while the other consists of one or more explosive compositions of lower melting point and this other component serves in a larger or small proportion as the melting component.

Cast bodies of such mixtures of explosive compositions are generally made of mixtures of hexogen (cyclotrimethylenetrinitramine), octogen (cyclotetramethylenetrinitramine) or nitropenta (tetranitropentaerythritol) and trinitrotoluene, whereby the last mentioned compound serves as the melting component. The reasons why nearly exclusively trinitrotoluene is used for producing casting mixtures can be found in its advantageous melting temperature of 80.8° C. and the fact that it can be safely handled. On the other hand, the detonation speed of trinitrotoluene is only 6900 meters per second and thus, the detonation speed of the casting mixtures containing trinitrotoluene will be considerably below that of hexogen or nitropenta.

It has also been proposed to compress pulverulent explosives with the addition of a small amount of a melting component. Thus, for instance hexogen has been desensitized with between 10 and 20% trinitrotoluene and the thus formed mixture has been compressed. In this manner a higher speed of detonation is obtained as can be obtained with conventional mixtures which have been compressed with the addition of wax. However, it is not possible in this manner to obtain the detonation speed of the pure compressed explosives. The density which can be obtained in this manner deviates even stronger from the theoretically obtainable density, since the explosive compositions which are used for desensitizing, such as trinitrotoluene are not as deformable as wax. Thus, a mixture consisting of 90% hexogen and 10% trinitrotoluene will result upon conventional compressing in an explosive body having a density which will be between 5 and 8% below the theoretically obtainable maximum density.

It is therefore an object of the present invention to overcome the above discussed disadvantages.

It is a further object of the present invention to produce a particularly effective high explosive body which may be safely handled and which can be easily produced.

Other objects and advantages of the present invention will become apparent from a further reading of the description and of the appended claims.

With the above and other objects in view, the present invention contemplates a high explosive body consisting essentially of an intimate mixture of a first explosive

2

composition and a second explosive composition, the second explosive composition being selected from the group consisting of (a) mixtures of between about 70 and 90% by weight trinitrobenzene and between about 30 and 10% by weight trinitrotoluene, and (b) mixtures of between about 20 and 80% by weight of trinitrobenzene and between about 80 and 20% by weight of tetryl, the first explosive composition having a significantly higher melting point than the second explosive composition.

The present invention is also concerned with a method of producing a high explosive body which comprises the steps of forming an intimate mixture of between 90 and 98% by weight of a first explosive composition selected from the group consisting of cyclotrimethylenetrinitramine, cyclotetramethylenetrinitramine and tetranitropentaerythritol and between 10 and 2% by weight of a second explosive composition selected from the group consisting of (a) mixtures of between about 70 and 90% by weight trinitrobenzene and between about 30 and 10% by weight trinitrotoluene, and (b) mixtures of between about 20 and 80% by weight of trinitrobenzene and between about 80% and 20% by weight of tetryl, subjecting the mixture to a partial vacuum, and compressing the thus evacuated mixture at the melting temperature of the second explosive composition so as to form a pressed high explosive body of the first and second explosive compositions.

According to another embodiment, the method of producing a high explosive body according to the present invention comprises the steps of forming an intimate mixture of between 50 and 80% by weight of a first explosive composition selected from the group consisting of cyclotrimethylenetrinitramine, cyclotetramethylenetrinitramine and tetranitropentaerythritol and between 50 and 20% by weight of a second explosive composition selected from the group consisting of (a) mixtures of between about 70 and 90% by weight trinitrobenzene and between about 30 and 10% by weight trinitrotoluene, and (b) mixtures of between about 20 and 80% by weight of trinitrobenzene and between about 80% and 20% by weight of tetryl, and casting the thus formed mixture so as to form thereof a cast high explosive body.

It has thus been found that particularly effective high explosive bodies which may be safely handled and are easily produced in an economical manner, are obtained by using as the melting component a mixture which consists essentially of between 70 and 90% trinitrobenzene and between about 30 and 10% trinitrotoluene. All percentage figures in the present specification are percent by weight.

Another mixture which may be advantageously used as the melting component according to the present invention consists of about 20-80% trinitrobenzene and between about 80 and 20% tetryl (trinitrophenyl-methylnitramine).

Mixtures of between 20 and 80% trinitrobenzene and between 80 and 20% tetryl solidify below 100° C. and are at such temperatures fully stable. They have a detonation speed of between 7300 and 7500 meters per second.

When high explosive bodies are to be produced by pressing, then the high melting component will preferably consist of between about 90 and 98% hexogen or

octogen or nitropenta, the balance being the low melting mixture described above, while in the case of cast high explosive bodies, the high melting component such as hexogen, octogen or nitropenta will form between about 50 and 80% of the explosive body and the balance will again be formed by one of the above described mixtures of either trinitrobenzene and trinitrotoluene or nitrobenzene and tetryl.

The utilization of the above described melting component within the indicated proportions will result in the production of high explosive bodies of an effectiveness or explosive yield which up to now could not be achieved. The detonation speed which is obtained with the high explosive bodies according to the present invention is approximately the same as that obtained with compressed pure hexogen or nitropenta.

Table 1 below describes the pertinent data which are obtained with cast bodies produced according to the present invention, as compared with cast bodies produced according to the prior art of hexogen and trinitrotoluene.

EXAMPLE

50 g. trinitrobenzene is mixed with 50 g. tetryl with a rubber-coated stirrer in a heatable evacuable copper vessel. The mixture is heated in a steam bath until the mass is completely molten and the temperature is about 95° C. 100 g. hexogen is added in 3-4 portions to the so prepared molten mass and the mixture is stirred to a homogeneous mass, the temperature being kept at 95° C. Then the apparatus is evacuated by means of an oil pump and the vacuum is maintained for 15 minutes at less than 1 mm. Hg. After the vacuum is removed the mixture is cast at about 95° C. in a cylindric

meters per second), although the proportion of the melting component is relatively high and consequently easy casting is assured. The new melting components can be utilized in all conventional casting methods for explosives which are used for obtaining homogeneous castings, for instance also under vacuum. As a non-melting component, particularly hexogen, octogen and nitropenta have been found to give very good results.

In addition to the data given in the table, it was found that very good results are also obtained by casting mixtures formed of between 20 and 50% of a mixture of about 70-90% trinitrobenzene and between about 30 and 10% trinitrotoluene, with between 50 and 80% hexogen, nitropenta or octogen.

Examples and data for producing pressed high explosive bodies according to the present invention are summarized in Table 2.

The compressed charges of Table 2 first section are prepared as follows.

10 30 g. trinitrobenzene is intimately mixed with 10 g. trinitrotoluene in a heatable copper vessel and heated to about 90° C. until both components are completely molten; then the mass is allowed to cool down by permanent stirring.

15 20 10 parts of this mixture are mixed with 90 parts of hexogen and the mass is heated to about 90° C. This mixture is filled into an evacuable matrix (30 mm. diameter) which has previously been heated to 90° C. The press die is placed on the mass and a compression of 1250 kg./cm.² is effected. The pressure is maintained until the matrix has cooled down to 30-40° C. The so obtained compressed charge has a density of 1.77 g./cm.³. The detonation velocity was found to be 8350 m./sec.

Table 2

Explosive Mixture		Press Power, kg./cm. ²	Press Temperature, °C.	Air Pressure, mm. Hg	Cooling	Density	Detonation Speed, m./sec.
Solid Component	Meltable Component						
90% hexogen-----	10% of a mixture of trinitrobenzene-trinitrotoluene 3:1.	1,200	90	10	Cooling under pressure-----	1.77	8,350
95% hexogen-----	5% of a mixture of trinitrobenzene-trinitrotoluene 3:1.	1,200	90	10	-----do-----	1.78	9,400
95% hexogen-----	5% of a mixture of trinitrobenzene-trinitrotoluene 3:1.	1,200	90	10	Expelled while still warm-----	1.73	8,300

mold of 25 mm. diameter and allowed to cool. The so obtained explosive column detonates at a velocity of 8000 m./sec.

Table 1

Composition	Detonation speed, m./sec.	Lead block bulging, cm./10 g.	Impact sensitivity according to koenen ¹ m.k.p.
50% hexogen-----	7,570	368	0.6
50% trinitrotoluene-----	7,660	378	0.6
60% hexogen-----	7,660	378	0.6
40% trinitrotoluene-----	8,000	435	0.6
50% hexogen-----	8,000	435	0.6
25% trinitrobenzene-----	8,200	445	0.6
25% tetryl-----	8,200	445	0.6
60% hexogen-----	8,200	445	0.6
24% trinitrobenzene-----	8,250	450	0.6

16% tetryl-----	8,000	450	0.4

¹ Explosivstoffe (E. Barth, Mannheim), 1958, p. 178.

It will be seen that the cast mixtures which include the melting component or mixture according to the present invention will give a detonation speed of up to 8300 meters per second, i.e. values which are close to those obtained with pure hexogen and nitropenta (8400

50 55 60 65 70 75 75 meters per second), although the proportion of the melting component is relatively high and consequently easy casting is assured. The new melting components can be utilized in all conventional casting methods for explosives which are used for obtaining homogeneous castings, for instance also under vacuum. As a non-melting component, particularly hexogen, octogen and nitropenta have been found to give very good results.

The best explosive bodies are prepared according to the present invention by compressing the mixture of the explosive components at a temperature at which the lower melting component is completely or partially molten and, preferably, compression of the mixture is carried out under a partial vacuum. Surprisingly it has been found that it is possible in this manner with a relatively very small proportion of the lower melting component in the explosive mixture to produce homogeneous and mechanically resistance high explosive bodies. The density of the thus produced high explosive body is only slightly below the theoretically possible maximum density and this is achieved by carrying out the compression under a partial vacuum, in other words, to subject the mixture to subatmospheric pressure, for instance of 10 millimeter mercury and to maintain this subatmospheric pressure and thus a very low gas content during the compressing of the mixture.

The method of producing pressed high explosive bodies according to the present invention can be carried out for instance by placing the press mold and the explosive mixture into a warming cabinet so that the mold as well as the mixture will be heated up to a temperature at which the lower melting component of the explosive mixture will be liquefied. Thereafter, the mold and the explosive mixture are quickly introduced into the press, evaporated and thereafter the mixture is compressed. The press molds are preferably fitted with rubber rings of circular cross section or other suitable packings and

are formed with a conduit for evacuating the interior of the press mold.

In order to obtain pressed bodies which conform fully to the shape of the mold, it is preferred to maintain the mold under pressure until the molten component of the explosive composition is again solidified, or to resiliently lock the mold after the same has been subjected to pressure, then to remove the locked mold, the interior of which is thus continued to be maintained under pressure, from the press and allow cooling off of the contents to take place outside of the press.

Although it is preferred, and the best results are achieved when the pressed body is maintained in the mold under compression until it is completely solidified, nevertheless, it is also possible to obtain the desired effect of increasing density and detonation speed when the pressed body is removed from the mold before the molten component of the body has been fully solidified.

Carrying out the method of the present invention is facilitated by using heatable press molds. For instance, the press molds may be heated electrically however, it is more desirable to provide the press form with conduits through which a heating fluid may pass.

Another manner in which the production of pressed high explosive bodies according to the present invention could be speeded up consists in the use of press forms which have a hot and a cold zone which can be achieved easily by passing heating and cooling liquids, respectively through the respective zones of the press mold. In this case, the preheated mixture is introduced into the hot or warm zone of the press mold, and compressed therein. Thereafter, the sleeve portion of the mold is moved relative to the press punch in such a manner that the pressed body may then be solidified while being located in the cold zone of the press.

By carrying out the warm pressing method of the present invention under a partial vacuum, for instance of a residual pressure of 10 mm. mercury, densities of the pressed body are obtainable which are only about 1% below the theoretically possible maximum density. The thus produced pressed bodies, depending on their composition, possess detonation speeds which are higher than those of pressed bodies formed of pure high explosive compositions.

Without further analysis, the foregoing will so fully reveal the gist of the present invention that others can by applying current knowledge readily adapt it for various applications without omitting features that, from the standpoint of prior art, fairly constitute essential characteristics of the generic or specific aspects of this invention and, therefore, such adaptations should and are intended to be comprehended within the meaning and range of equivalence of the following claims.

What is claimed as new and desired to be secured by Letters Patent is:

1. A high explosive body consisting essentially of an intimate mixture of a first explosive composition and a second explosive composition, said second explosive composition being selected from the group consisting of (a) mixtures of between about 70 and 90% by weight trinitrobenzene and between about 30 and 10% by weight trinitrotoluene, and (b) mixtures of between about 20 and 80% by weight of trinitrobenzene and between about 80 and 20% by weight of tetryl, said first explosive composition having a significantly higher melting point than said second explosive composition.

2. A high explosive body consisting essentially of an intimate mixture of a first explosive composition selected from the group consisting of cyclotrimethylenetrinitramine, cyclotetramethylenetrinitramine and tetraniropentaerythritol, and a second explosive composition, said second explosive composition being selected from the group consisting of (a) mixtures of between about 70 and 90% by weight trinitrobenzene and between about 30 and 10% by weight trinitrotoluene, and (b) mixtures

of between about 20 and 80% by weight of trinitrobenzene and between about 80 and 20% by weight of tetryl, said first explosive composition having a significantly higher melting point than said second explosive composition.

3. A pressed high explosive body consisting essentially of an intimate mixture of between 90 and 98% by weight of a first explosive composition selected from the group consisting of cyclotrimethylenetrinitramine, cyclotetramethylenetrinitramine and tetraniropentaerythritol, and between 10 and 2% by weight of a second explosive composition, said second explosive composition being selected from the group consisting of (a) mixtures of between about 70 and 90% by weight trinitrobenzene and between about 30 and 10% by weight trinitrotoluene, and (b) mixtures of between about 20 and 80% by weight of trinitrobenzene and between about 80 and 20% by weight of tetryl, said first explosive composition having a significantly higher melting point than said second explosive composition.

4. A cast high explosive body consisting essentially of an intimate mixture of between 50 and 80% by weight of a first explosive composition selected from the group consisting of cyclotrimethylenetrinitramine, cyclotetramethylenetrinitramine and tetraniropentaerythritol, and between 50 and 20% by weight of a second explosive composition, said second explosive composition being selected from the group consisting of (a) mixtures of between about 70 and 90% by weight trinitrobenzene and between about 30 and 10% by weight trinitrotoluene, and (b) mixtures of between about 20 and 80% by weight of trinitrobenzene and between about 80 and 20% by weight of tetryl, said first explosive composition having a significantly higher melting point than said second explosive composition.

5. A method of producing a high explosive body comprising the steps of forming an intimate mixture of between 90 and 98% by weight of a first explosive composition selected from the group consisting of cyclotrimethylenetrinitramine, cyclotetramethylenetrinitramine and tetraniropentaerythritol and between 10 and 2% by weight of a second explosive composition selected from the group consisting of (a) mixtures of between about 70 and 90% by weight trinitrobenzene and between about 30 and 10% by weight trinitrotoluene, and (b) mixtures of between about 20 and 80% by weight of trinitrobenzene and between about 80 and 20% by weight of tetryl; subjecting said mixture to a partial vacuum; and compressing the thus evacuated mixture at the melting temperature of said second explosive composition so as to form a pressed high explosive body of said first and second explosive compositions.

6. A method of producing a high explosive body comprising the steps of forming an intimate mixture of between 50 and 80% by weight of a first explosive composition selected from the group consisting of cyclotrimethylenetrinitramine, cyclotetramethylenetrinitramine and tetraniropentaerythritol and between 50 and 20% by weight of a second explosive composition selected from the group consisting of (a) mixtures of between about 70 and 90% by weight trinitrobenzene and between about 30 and 10% by weight trinitrotoluene, and (b) mixtures of between about 20 and 80% by weight of trinitrobenzene and between about 80 and 20% by weight of tetryl; and casting the thus formed mixture so as to form thereof a cast high explosive body.

7. A method of producing a high explosive body comprising the steps of forming an intimate mixture of between 90 and 98% by weight of a first explosive composition selected from the group consisting of cyclotrimethylene trinitramine, cyclotetramethylenetrinitramine and tetraniropentaerythritol and between 10 and 2% by weight of a second explosive composition selected from

the group consisting of (a) mixtures of between about 70 and 90% by weight trinitrobenzene and between about 30 and 10% by weight trinitrotoluene, and (b) mixtures of between about 20 and 80% by weight of trinitrobenzene and between about 80 and 20% by weight of tetryl; subjecting said mixture to a subatmospheric pressure of about 10 mm. mercury; and compressing the thus evacuated mixture at a pressure of about 1,200 kg./cm.² and at a temperature at which at least a portion of said second explosive composition will be in molten state so as

5 to form a pressed high explosive body of said first and second explosive compositions.
